UNITED STATES PATENT OFFICE.

JOSEPH P. BELAND, OF QUEBEC, QUEBEC, CANADA.

BOTTOM AND TOP PAGE MARGINER.

1,376,996.

Specification of Letters Patent.

Patented May 3, 1921.

Application filed June 10, 1919. Serial No. 303,048.

To all whom it may concern:

Be it known that I, JOSEPH P. BELAND, subject of the King of England, resident of Quebec city, in the Province of Quebec and 5 Dominion of Canada, have invented new and useful Improvements in Bottom and Top Page Marginers, of which the following is a specification.

The object of the invention is to provide 10 an apparatus in the form of an attachment applicable to various standard and other types of typewriting machines for determining top and bottom margins of pages with accuracy to facilitate the securing of 15 uniformity in the operation of the machine in continuous or plural page work without involving the necessity of experiment or loss of time incident to closely watching the progress of the work.

20 Further objects and advantages will appear later it being understood that changes in form, proportion and details may be resorted to particularly in adapting the attachment to various kinds of machines, without departing from the spirit of the invention.

In the drawings:

Figure 1 is a plan view of the device applied in the operative position to a typewriting machine.

Fig. 2 is a side view of the same.

Fig. 3 is a section on the line 3—3 of Fig. 1.

Fig. 4 is a plan view of the endless gage 35 element.

In the construction illustrated a continuous or endless gage element 10 is employed to traverse a guide roll 11 mounted upon the spindle 12 of the platen 13 of the typewriting machine and an idle or guide roll 14 supported by a suitable bracket 15 and of a sufficient diameter to support the gage member, consisting in this instance of a tape, at a proper degree of tautness. The 40 gage member is graduated to represent space between lines of writing of the typewriting machine and numbered consecutively as for example from 1 to 95 for a standard legal size sheet having a length of 13½ inches. 45 Obviously the length of the gage member and the number of graduations may be varied to suit the length of the page or the character of the work or the spacing of the machine, or if, with a standard gage adapted 50 for the 13½ inch page in use, a sheet of less

length may be employed, as for example of the letter size, simply by determining the length of said sheet by any suitable measure, and utilizing only that portion of the gage which is represented by such length. 60 The guide roll 14 is loose for movement in either direction to correspond with the movement of the operating roll 11 which while loosely mounted upon the spindle of the platen to permit of adjustment to bring 65 the proper graduation thereof in registration with the top edge of a sheet inserted in the typewriting machine, is adapted to be turned with the platen during the feeding movement thereof as the writing progresses from line to line. To this end any suitable means of connection may be employed such as a pawl and ratchet 16 and 17 so that while the roll 11 will receive motion 70 from the platen during the feeding movement of the latter, the said roll is capable of an independent movement to secure the proper initial adjustment thereof.

The pawl 16 being carried by the guide 75 roll 11 and the ratchet wheel being carried by the platen spindle, motion is communicated to the guide roll by the spindle and the ratchet teeth are so disposed that endless motion will be communicated when the platen roll is fed forwardly, as in writing.

In operation, assuming that a standard 80 13½ inch page is being employed, it should be determined at what graduation of the gage member the first line of the writing shall appear, as for example, the tenth 85 space, to thus determine the amount of the top margin. The writing may then progress in the ordinary way without attention on the part of the operator until it has reached a point near the bottom of the page which 90 may be determined upon to leave the proper bottom margin. As the graduation of the gage member reads backwardly the number of line spaces remaining on the sheet 95 at any point in the progress of the writing will be indicated by the gage so that if it is desired to leave a five line space at the bottom of the page the writing may terminate at that point or when the gage member indicates that there are five remaining line 100 spaces on the sheet. Having determined upon these graduations as the guides for the top and bottom margins it is a comparatively simple matter to start and end the writing on each successive sheet in accord- 105 110

ance therewith, so that at the end of the operation the several sheets have corresponding top and bottom marginal spaces.

Having described the invention I claim:

- 5 A page margining attachment for typewriting machines having an operating roll mounted for independent movement coaxially with the platen of a typewriting machine, means for communicating forward 10 step by step movement from the platen to

said operating roll, an idle guide roll, and a gage member consisting of an endless plate or tape traversing said rolls and having graduations representing line spaces numbered consecutively in reverse order. 15

In testimony whereof I affix my signature.

JOSEPH P. BELAND.
